MARINE VESSEL LOCATING AND LIFTING APPARATUS

Richard B. Luby, Chicago, Ill.

Application January 15, 1943, Serial No. 472,445

13 Claims. (Cl. 114—51)

This invention relates to a combination locating and lifting or hoisting apparatus which is especially adapted for lifting submerged or sunken marine vessels.

An object of the invention is to afford a novel and relatively simple and efficient apparatus by means of which a submerged or sunken marine vessel may readily be located and lifted by employing in conjunction with the invention any suitable marine lifting or hoisting apparatus.

An additional object of the invention is to afford a novel combination pilot cable and reel and lifting cable and reel by means of which a submerged or sunken vessel may be located and lifted by employing in conjunction therewith any suitable marine hoisting or lifting apparatus.

Another object of the invention is to provide a novel collapsible cable-supporting reel structure which is embodied in the invention.

Other and further objects of the present invention will be apparent from the following description and claims and will be understood by reference to the accompanying drawings which, by way of illustration, show preferred embodiments and the principles thereof and what I now consider to be the best modes in which I have contemplated applying those principles. Other embodiments of the invention embodying the same or equivalent principles may be used and structural changes may be made as desired by those skilled in the art without departing from the present invention and the purview of the appended claims.

In the drawings,

Fig. 1 is a diagrammatic top plan view of a typical marine vessel with which the invention may be employed and showing a typical arrangement of six of the new locating and lifting units around and upon said vessel;

Fig. 2 is a diagrammatic side elevational view of the vessel shown in Fig. 1;

Fig. 3 is an enlarged vertical sectional view on line 3—3 in Fig. 1 illustrating one of the new combination locating and lifting units in its normal or ineffective position;

Fig. 4 is a view on line 4—4 in Fig. 3 partly in section and partly in side elevation;

Fig. 5 is a vertical sectional view taken on line 5—5 in Fig. 4;

Fig. 6 is a fragmentary vertical sectional view on line 6—6 in Fig. 5;

Fig. 7 is a detail view on line 7—7 in Fig. 5, illustrating one of the bearing units which support the axially outer end portions of the two complementary parts of the shaft which supports the pilot cable reel;

Fig. 8 is a view showing one of the new combination locating and lifting units with the pilot cable and its collapsible supporting reel raised and showing the lifting cable unwound from its supporting reel;

Fig. 9 is a perspective view showing the two complementary sections of the hub embodied in the new collapsible supporting reel for the pilot cable; and

Fig. 10 is a sectional plan view on line 10—10 in Fig. 8.

A conventional marine surface vessel is diagrammatically shown in Figs. 1 and 2 of the drawings, wherein it is generally indicated at 10, and is shown as having six of the new combination indicating or locating and lifting units arranged thereon and therearound. Each of the combination indicating or locating and lifting units is generally indicated at 11 and while the units 11 are shown as being arranged upon and associated with a marine surface vessel, it will be understood that they may be likewise used in connection with submarine vessels.

The weather deck of the vessel 10 is indicated at 12 and, as shown in Figs. 3 and 4, each of the new combination locating and lifting units 11 is so arranged that most of the operating parts thereof lie immediately below the weather deck 12.

In general, it may be said that each of the new combination locating and lifting units 11 includes a buoyant float 13 which may be made of cork or any other suitable buoyant material. The float 13 is attached to a relatively small or light flexible pilot cable 14 which is wound upon a collapsible supporting reel 15 and each of the combination locating and lifting units 11 also includes a relatively heavy or strong flexible lifting or hoisting cable 16 which is wound upon a supporting reel 17.

The construction and arrangement of each of the new combination indicating or locating and lifting units 11 is, in general, such that if the vessel 10 should sink the buoyant float 13 may be released to float toward the surface of the water and thus carry with it the pilot cable 14, and when the pilot cable 14 becomes unwound from its supporting reel 15, the reel 17 collapses and becomes detached from its support and parts thereof tend to rise with the pilot cable 14 and the float 13, as indicated in Fig. 8 of the drawings. Hence, it will be seen that when the buoyant float 13 reaches the surface of the water in which the vessel 10 is sunk, said float 13 provides a marker or indicator for locating the sunken

vessel and inasmuch as a plurality of the units 11 are preferably arranged at selected points around and upon the vessel 10, it becomes possible to raise or hoist the sunken vessel through the use of the hoisting or lifting cables 16 and any suitable marine hoisting or lifting apparatus which may be employed in conjunction therewith. It will be understood, in this connection, that the pilot cable 14 and the hoisting cable 16 are preferably of sufficient length such, for example, as 500 feet or more each, to permit usage thereof in water having such a depth as will permit the practical raising of sunken marine vessels by means of known methods and apparatus.

Having thus outlined generally the purpose and operation of the invention, a detailed description of the typical embodiment thereof which is shown in the drawings will now be given.

It will be noted by reference to the drawings that the supporting reel 17 for the lifting or hoisting cable 16 includes bearing trunnions 18 which are suitably journaled in heavy bearing blocks 19. The bearing blocks 19 are anchored or mounted upon the bottom wall 20 of a watertight housing 21 which is preferably suspended from and immediately below the weather deck 12 of the vessel 10 and which is preferably secured thereto in any suitable manner as by welding 22.

One end portion of the lifting cable 16 is permanently secured or attached to the reel 17 and a flexible connecting element 23 is attached to the other end portion of the lifting cable 16, the flexible connecting element 23 being divided to provide two arms 24 and 25.

One arm 24 of the flexible connecting element 23 is, as is best shown in Fig. 5, attached to a connecting element or link 26 and this link 26 is swivelly mounted upon a section 27 of the supporting shaft for a collapsible pilot cable reel, which is generally indicated at 28, and on which the pilot cable 14 is normally wound.

The other arm 25 of the flexible connecting element 23, is, as is also shown in Fig. 5, attached to a connecting element or link 29 which is swivelly mounted upon a section 30 of the supporting shaft for the collapsible reel 28, and which shaft section 30 is complementary to the shaft section 27.

The collapsible reel 28 includes a reel flange or wheel 31 which is preferably made of buoyant material such, for example, as wood, and this reel flange 31 is fixed upon the shaft section 27. The collapsible reel 28 also includes a corresponding and complementary reel flange or wheel 32 which is fixed upon the shaft section 30.

As shown in the drawings, the axially inner ends of the complementary shaft sections 27 and 30 are interconnected by a flexible connecting element 33 which is also attached to the lower or inner end portion of the flexible pilot cable 14.

The shaft section 27 of the collapsible reel structure 28 has a ball-like element 34 fastened or formed thereon and a similar ball-like element 35 is fastened or formed upon the complementary shaft section 30.

As shown in the drawings, a spacing collar 36 is adjustably secured upon the shaft section 27, axially outwardly of the swivelled connecting link 26, and a similar spacing collar 37 is adjustably mounted upon the shaft section 30, axially outwardly of the swivelled connecting link 29.

The reel structure 28 includes a collapsible hub structure, which is generally indicated at 38, and which is best shown in Fig. 9, wherein it is shown in disassembled or collapsed position. The hub structure 38 of the collapsible reel 28 in-

cludes two complementary hub sections 39 and 40 which are preferably made of buoyant material such, for example, as wood, and which hub sections when assembled, cooperate to form a cylindrical hub for the reel structure 28. The hub section 39 is provided with an axially extending groove 41 for the reception of parts of the shaft sections 27 and 30, and the hub section 40 is provided with a corresponding and complementary axially extending groove 42 for the reception of parts of the shaft sections 27 and 30.

As best shown in Fig. 9, the hub part 39 is provided with a recess or depression 43 for the reception of part of the ball-like element 34 on the shaft section 27, and the hub section 40 is provided with a complementary depression or recess 44 for the reception of part of the ball-like element 34 on the shaft section 27, these recesses 43 and 44 cooperating to provide a socket for the reception of the ball-like element 34 on the shaft section 27.

As likewise shown in Fig. 9, the hub section 39 is provided with a depression or recess 45 for the reception of part of the ball-like element 35 on the shaft section 30 and the hub section 40 is provided with a complementary depression or recess 46 for the reception of part of the ball-like element 35 on the shaft section 30. These recesses 45 and 46 cooperate to provide a socket for the reception of the ball-like element 35 on the shaft section 30 and it will be noted, in this connection, that when the ball-like elements 34 and 35 are disposed in the sockets 43-44 and 45-46 provided in the hub sections 39 and 40 they preferably have sufficient frictional engagement with the walls of the sockets 43-44 and 45-46 to maintain the hub sections 39 and 40 together and the shaft sections 27 and 30 in axial alignment. In this manner the collapsible hub 38 is normally maintained in assembled position.

The axially outer end portion of the shaft section 27 of the collapsible reel structure 28 is journaled in a bearing block 47 and, as shown in Figs. 5 and 7 of the drawings, this bearing block 47 is pivotally or rockably mounted, by means of trunnions 48, in a supporting block or frame 49. The supporting block or frame 49 is attached to a vertically extending side wall 50 of a housing 51 which is arranged within the housing 21 and encloses the collapsible reel structure 28 and the pilot cable 14 and the buoyant float 13 when these parts are disposed in their normal or ineffective position. It will be noted, in this connection, that while the body of the housing 51 is disposed within the larger housing 21, and lies below the weather deck 12, the housing 51 includes a portion which projects above the weather deck 12, as shown in Figs. 3, 4, 5 and 6 of the drawings.

The axially outer end portion of the shaft section 30 is journaled in a bearing block 52 and this bearing block 52 is pivotally mounted, as at 53, in a supporting frame or block 54 which is attached to the opposite vertically extending wall 55 of the housing 51, as best shown in Fig. 5 of the drawings.

It will be noted, in this connection, that the axially outer end portion of the shaft section 27 is slidably inserted into a centrally arranged bearing opening 56 which is formed in the pivoted bearing block 47 and the axially outer end portion of the shaft section 30 is slidably inserted into a similar centrally arranged bearing opening 57 which is formed in the pivoted bearing block 52.

As shown in the drawings, that portion of the housing 51 which projects above the weather deck 12 is provided with a closure or cover 58 which is hingedly mounted upon the upper portion of the side wall 55 of the housing 51, as indicated at 59.

The cover or door 58 is provided with a handle 69 and the door 58 is normally held down in watertight engagement with the upper edges of the side walls of the housing 51 by means of a clamping unit 60. This clamping unit 60 includes a clamping bracket 61 and this bracket 61 includes an arm 62 which is adapted to bear upon the closure or door 58 at the end thereof opposite its hinge mounting 59. The clamping bracket 61 is swivelly mounted upon a clamping screw 63 and the lower end portion of the clamping screw 63 is anchored to the weather deck 12 of the vessel 10 in any suitable manner as by welding. A clamping nut 64 is mounted upon the screw 63 and a manually operable handle 65 is attached to the clamping nut 64. It will thus be seen that the clamping nut 64 and handle 65 may be turned upon and relative to the screw 63 so as to clamp the bracket 61 in effective or clamping position upon and relative to the door 58, as in Figs. 3 and 5, and that the clamping nut 64 and handle 65 may be turned upon and relative to the screw 63 so as to release the door 58 and thus enable the door 58 to be moved into open position, as in Fig. 8, as and when desired.

A retaining latch 66 is pivotally mounted, as at 67, on the weather deck 12, adjacent the housing 51, and the latch 66 is provided with a handle 68.

It will also be noted that a screen 70 is attached, in any suitable manner, to the otherwise open bottom of the housing 51 and this screen 70 is provided with a slot 71 (Fig. 10) through which the pilot cable 14 extends. This screen 70 serves to prevent parts of the collapsible reel structure 28 from falling through the bottom of the housing 51 and becoming fouled when the reel structure 28 is collapsed while the slot 71 in the screen 70 enables the pilot cable 14 and the lifting cable 16 to pass therethrough.

Since all of the units 11 are identical in structure and operate in the same manner, the use and operation of only one of the same will now be described in detail, it being understood that the following description applies to all of the other units 11.

The parts of each of the units 11 are normally arranged in ineffective position, and in which position they are shown in Figs. 3, 4, 5 and 6 of the drawings. When the parts are thus disposed the lifting cable 16 is wound upon its supporting reel 17, the pilot cable 14 is wound upon the then assembled collapsible reel structure 28, the buoyant float 13 and the collapsible reel structure 28 are arranged within the housing 51, and the door 58 of the housing 51 is closed and held in closed position by the clamping unit 60.

However, if the vessel 11 should become damaged and appear to be in sinking condition, the clamping unit 60 may be released from clamping engagement with the door 58 and moved into ineffective position, in which it is shown in Fig. 8, this being accomplished by manipulating the handle 65 and the clamping nut 64 upon and relative to the screw 63. The door 58 of the housing 51 may then be swung into open position, upon its hinge 59, by grasping the handle 69, whereupon

the door 58 may be held in open position by means of the latch 66, as shown in Fig. 8.

Accordingly, as and when the vessel 11 sinks water will enter the housing 51, through the then open top thereof, thus causing the buoyant float 13 to rise out of the housing 51 and thereby unwinding the pilot cable 14 from the collapsible reel structure 28. As the pilot cable 14 is thus unwound from the reel 28 the collapsible reel unit 28 rotates upon its supporting shaft sections 27 and 30 which, in turn, rotate in the bearing openings 56 and 57 which are provided therefor in the pivoted bearing blocks 47 and 52, respectively.

15 However, when the buoyant float 13 has risen sufficiently to completely unwind the pilot cable 14 from its supporting reel 28, further upward movement of the float 13 will collapse the reel structure 28 and parts of the reel structure 28 will tend to rise with the float 13.

It will be noted, in this connection, that the axially inner end portions of the shaft sections 27 and 30 are interconnected by the flexible connecting element 33 which, in turn, is connected 25 to the inner or lower end portion of the pilot cable 14. Accordingly, as and when the pilot cable 14 becomes completely unwound from the hub 38 of the reel structure 28, further upward movement of the float 13 will act, through the pilot cable 14 and the flexible connecting element 33, and the shaft sections 27 and 30, to pivot the bearing blocks 47 and 52, upon their supporting trunnions 48 and 53, respectively, thereby pivoting the bearing blocks 47 and 52 35 from their normal or effective position, as in Fig. 5, into the position in which they are shown in Fig. 8. Accordingly, as the upward motion of the float 13, pilot cable 14 and flexible connecting element 33 continues, the shaft sections 27 and 40 30 will be pulled out of the bearing openings 56 and 57 which are provided therefor in the bearing blocks 47 and 52, respectively, and the shaft sections 27 and 30 and the wheels 31 and 32 of the reel structure 28 will thereupon rise with the 45 float 13 and the pilot cable 14, as shown in Fig. 8. During this operation the hub sections 39 and 40 will be dislodged from the shaft sections 27 and 30 of the collapsible reel structure 28 and since the hub sections 27 and 30 and the reel flanges 31 and 50 32 are preferably made of wood or like material they will tend to rise and float with the float 13.

As the various floats 13 thus rise to the surface of the water in which the vessel 11 may be sunk, the floats 13 provide indicators or markers for 55 locating the sunken vessel and when the vessel has been located the flexible lifting cables 16 may be raised and any suitable marine hoisting or lifting apparatus may be operatively connected to or associated with the various lifting cables 16 60 to enable the sunken vessel 10 to be raised. It will be noted, in this connection, that upward or lifting pull exerted upon the lifting cables 16 will act, through the bearing blocks 19, housing 21, and the weather deck 12 to exert a lifting 65 action upon the submerged vessel 10.

It will be noted that the shaft sections 27 and 30 of the collapsible reel structure 28 are swivelly connected by the links 26 and 29 to the arms 24 and 25, respectively, of the flexible connecting element 23 and that the flexible connecting element 23, in turn, is connected to the lifting cable 16. Hence, it will be seen that the pilot cable 14 may be employed to raise the lifting cable 16 and thus unwind the lifting cable 16 from its sup-

porting reel 17, whereupon the lifting cable 16 may be employed in raising the sunken vessel.

It will thus be seen from the foregoing description, considered in conjunction with the accompanying drawings, that the present invention accomplishes its intended objects, and has the desirable advantages and characteristics, including those hereinbefore pointed out and others which are inherent in the invention.

While I have illustrated and described selected embodiments of my invention, it is to be understood that these are capable of variation and modification and I therefore do not wish to be limited to the precise details set forth but desire to avail myself of such changes and alterations as fall within the purview of the following claims.

I claim:

1. In a combination marine vessel locating and lifting apparatus, the combination of: a buoyant float adapted to be released for rising movement upon the sinking of said vessel, a relatively light flexible pilot cable attached to said buoyant float, means for supporting said pilot cable upon said marine vessel including a rotatable supporting reel, means for detachably mounting said supporting reel upon said vessel so that said supporting reel will be lifted by and rise with said buoyant float when said pilot cable becomes completely unwound from said supporting reel, and a relatively heavy strong flexible lifting cable operatively connected to said pilot cable supporting reel for lifting said vessel.

2. A combination marine vessel locating and lifting apparatus as defined in claim 1 and which includes a supporting reel adapted to be rotatably mounted in the body of said vessel for supporting said lifting cable, and means adapted to be anchored in the body of said vessel for supporting said lifting cable supporting reel.

3. In a device of the character described, the combination of: a buoyant float adapted to be mounted upon a marine vessel in position to be released for rising movement upon sinking of said vessel, a flexible pilot cable connected to said buoyant float, means for supporting said pilot cable including a collapsible supporting reel adapted to be rotatably mounted upon said vessel, and means for detachably mounting said collapsible supporting reel structure upon said vessel so that upon the rising movement of said float said pilot cable will be unwound from its said collapsible supporting reel and upon being unwound therefrom will raise said collapsible supporting reel therewith upwardly relative to and away from said vessel.

4. In a device of the character described, the combination of a buoyant float adapted to be mounted upon a marine vessel in position to be released to rise therefrom upon sinking of said vessel, a flexible pilot cable connected to said buoyant float, means for supporting said pilot cable including a collapsible reel structure, means for detachably mounting said collapsible reel structure in the body of said vessel so that upon rising movement of said float said pilot cable will be unwound from its said collapsible supporting reel and upon being unwound therefrom will raise its said collapsible supporting reel therewith out of the vessel, said collapsible supporting reel including a pair of complementary and normally axially aligned shaft sections each having an axially outer end portion, a reel flange carried by each of said shaft sections, a pair of bearing blocks adapted to be pivotally mounted in the body of said vessel and

each having a bearing opening provided therein for the slidable reception of the axially outer end portion of one of said shaft sections, said collapsible reel structure including a collapsible

hub structure disposed about said shaft sections and normally retaining said shaft sections in axial alignment, and a flexible connecting element having a portion connected to the axially inner end of each of said shaft sections and having a portion connected to said pilot cable.

5. A device as defined in claim 4 in which each of said shaft sections has a ball-like element formed thereon and in which said collapsible hub structure includes a pair of complementary hub sections each having spaced recesses formed therein and in which said spaced recesses cooperate to form a pair of sockets for the reception of the said ball-like elements upon said shaft sections.

6. A collapsible reel comprising a pair of normally axially aligned shaft sections, a hub structure including complementary hub sections normally carried by said shaft sections and retaining said shaft sections in axial alignment, a relatively stationary support at the axially outer end of each of said shaft sections, and a bearing block pivotally mounted upon each of said supports, each of said supports having a bearing opening formed therein for the reception of the axially outer end portion of one of said shaft sections.

7. A collapsible reel structure as defined in claim 6 which includes a flexible connecting element having a portion connected to the axially inner end portion of each of said shaft sections and having a portion adapted to be connected to a flexible cable windable upon said hub structure.

8. A flexible reel structure as defined in claim 6 in which each of said shaft sections has a ball-like element formed thereon and in which each of said complementary hub sections has a pair of spaced recesses formed therein and which said spaced recesses cooperate to form a pair of sockets for the reception of said ball-like elements.

9. An apparatus for locating and raising a marine vessel, comprising the combination of: a flexible cable-supporting reel, means for rotatably mounting said reel upon a marine vessel, a flexible and relatively heavy lifting cable normally wound upon said reel, a buoyant float adapted to be carried by said vessel and to be released therefrom upon sinking of said vessel, a relatively light pilot cable operatively connected to said buoyant float, a collapsible supporting reel normally rotatably mounted upon said vessel for supporting said pilot cable, and means for releasably mounting said collapsible supporting reel upon said vessel, said collapsible supporting reel for said pilot cable being releasable from its said mounting means upon said vessel and being lifted upwardly by said buoyant float when said pilot cable becomes completely unwound from its said supporting reel so that further upward movement of said float and said collapsible reel will unwind said lifting cable from its said supporting reel.

10. An apparatus for locating and raising a marine vessel, comprising the combination of: a flexible cable-supporting reel, means for rotatably mounting said reel upon a marine vessel, a flexible and relatively heavy lifting cable normally wound upon said reel, a buoyant float adapted to be carried by said vessel and to be released therefrom upon sinking of said vessel, a relatively light pilot cable operatively connected

to said buoyant float, a collapsible supporting reel normally rotatably mounted upon said vessel for supporting said pilot cable, and means for releasably mounting said collapsible supporting reel upon said vessel, said collapsible supporting reel for said pilot cable being releasable from its said mounting means upon said vessel and being lifted upwardly by said buoyant float when said pilot cable becomes completely unwound from its said supporting reel so that further upward movement of said float and said collapsible reel will unwind said lifting cable from its said supporting reel, said collapsible supporting reel for said pilot cable including a pair of normally aligned shaft sections each having a reel flange thereon, said mounting means for said collapsible reel including a pair of relatively stationary supporting members mounted in the body of said vessel and a bearing block pivotally mounted in each of said stationary supports, each of the said bearing blocks having a bearing opening therein and the axially outer end portion of each of said shaft sections being slidably mounted in the said bearing opening in one of said bearing blocks whereby when said pilot cable becomes completely unwound from its said collapsible supporting reel further upward movement of said buoyant float will act, through said pilot cable and said shaft sections, to pivot said bearing blocks upon their aforesaid supporting members and thus slide the said axially outer end portions of said shaft sections out of the said bearing openings provided therefor in said pivoted bearing blocks.

11. An apparatus as defined in claim 10 in which said collapsible supporting reel structure for said pilot cable includes a pair of comple-

mentary hub sections disposed between the said reel flanges of said collapsible supporting reel for said pilot cable and in which said complementary hub sections are detachably connected to said shaft sections.

- 5 12. An apparatus as defined in claim 10 in which said collapsible supporting reel structure includes a pair of complementary hub sections disposed between the flanges of said collapsible supporting reel and in which said complementary hub sections are detachably connected to said shaft sections, and in which each of said shaft sections has a ball-like element thereon and in which each of said complementary hub sections is provided with a pair of spaced recesses and in which said spaced recesses cooperate to provide a pair of sockets for the reception of said ball-like elements on said shaft sections.
- 10 13. An apparatus as defined in claim 10 in which said collapsible supporting reel structure includes a pair of complementary hub sections disposed between the flanges of said collapsible supporting reel and in which said complementary hub sections are detachably connected to said shaft sections, and in which each of said shaft sections has a ball-like element thereon and in which each of said complementary hub sections is provided with a pair of spaced recesses and in which said spaced recesses cooperate to provide a pair of sockets for the reception of said ball-like elements on said shaft sections, and which apparatus includes a flexible connecting element having a portion attached to the axially inner end portion to each of said shaft sections and having a portion attached to the inner or lower end portion of said pilot cable.
